GARMENT HANGER

Alexander S. Práger, New York, N. Y.

Application August 23, 1948, Serial No. 148,249

Term of patent 7 years

(Cl. D80—8)

To all whom it may concern:

Be it known that I, Alexander S. Práger, a citizen of Hungary, residing at New York, in the county of New York and State of New York, have invented a new, original, and ornamental Design for Garment Hangers, of which the following is a specification, reference being had to the accompanying drawing, forming a part thereof.

In the drawing:

Fig. 1 is a front elevational view of a garment hanger, showing my new design;

Fig. 2 is a top view of the same;

Figs. 3 and 4 are sectional details on the lines 3—3 and 4—4 of Fig. 1, respectively.

I claim:

The ornamental design for a garment hanger, as shown.

ALEXANDER S. PRÁGER.
